LANDING AND LAUNCHING EQUIPMENT FOR
FLYING BOATS

Frank J. Walters, Cocoa, Fla.

Application August 22, 1944, Serial No. 550,593

5. Claims. (Cl. 61—67)

My invention relates to improvements in landing and launching equipment for flying boats, or seaplanes.

The invention is designed with the primary objects in view of reducing time and labor incident to landing and launching flying boats, or seaplanes, reducing the accident hazard to a minimum, and accelerating both handling and launching, all regardless of the tide conditions and high winds.

Other objects are to provide equipment for landing and launching such boats under their power with safety, and with the aid of greatly reduced personnel as compared with present day requirements.

Still another object is to provide equipment for accomplishing the above objectives which is comparatively inexpensive to install, operate and service.

Other and subordinate objects are also comprehended by my invention, all of which, together with the precise nature of my improvements, will be readily understood when the succeeding description and claims are read with reference to the drawings accompanying and forming part of this specification.

In said drawings:

Figure 1 is a view in top plan illustrating my invention in a preferred embodiment thereof, and the manner in which the pilot slip is set in landing a flying boat approaching at an angle to the floating section of the landing ramp.

Figure 2 is a fragmentary view in longitudinal section taken on the line 2—2 of Figure 1 and illustrating the flying boat seated on the transporting car.

Figure 3 is a view in plan of the same.

Figure 4 is a similar view drawn to an enlarged scale and with parts omitted for clearness of illustration.

Figure 5 is a fragmentary view in side elevation illustrating the manner in which the pilot slip and floating ramp section rise and fall with the tides.

Figure 6 is a view in transverse section taken on the line 6—6 of Figure 5 and drawn to a further enlarged scale.

Figure 7 is a similar view taken on the line 7—7 of Figure 5.

Figure 8 is a fragmentary view in top plan of one of the side guide walls of the floating ramp section, and one of the side wings of the pilot slip.

Figure 9 is a view in top plan of the transporting car.

Figure 10 is a view in side elevation of the same. Figure 11 is a view in transverse section taken on the line 11—11 of Figure 9.

Figure 12 is a view in top plan of a modified embodiment of my invention.

Figure 13 is a fragmentary view in side elevation of the same.

Referring to the drawings by numerals, and particularly to Figures 1 to 11, my improved landing and launching equipment, in the preferred embodiment illustrated, comprises a stationary landing platform 1 which may take various forms, preferably that of an island, built up in the water, of any suitable material, to a height above high tide water level for landing flying boats, or seaplanes, thereon, and which may be of any desired shape or size.

At one side of the platform 1, a landing ramp 2 is provided to incline downwardly therefrom into the water, to a depth suitable for a purpose presently seen. The ramp 2 comprises an elongated track bed 3 supported by piles 4 and supporting car tracks 5 for the passage of a car, presently described, up the ramp and onto said platform 1.

A launching ramp 6 similar to the landing ramp 2, but longer for a purpose presently seen, and likewise provided with car tracks 7, leads from said platform 1, preferably from the same side as the landing ramp, 2.

A track system is provided on the platform 1, including tracks 8 forming an extension of the tracks 5, tracks 9 of which the tracks 7 form an extension, and cross-over tracks 10 between the tracks 8 and 9, together with suitable switches indicated generally at 11, 12 for closing, or opening, the cross-over tracks 10 as desired. The tracks 8 may lead to such adjuncts as refueling stations, hangars, scales, or other landing field equipment, not shown, since the same form, per se, no part of the present invention.

At the outer, or submerged, end of the landing ramp 2, a floating pilot ramp section is provided comprising a track bed 14 of a suitable length, for a purpose presently apparent, arranged in end-to-end relation to the landing ramp 2, car tracks 15 thereon leading to the tracks 5, and side guide walls 16 preferably covered on the opposed faces of the same with heavy padding designated 17. The track bed 14 of the floating ramp section 13, as best shown in Figures 5, 6, 7 and 8, is disposed between pairs of piles 18, 19 arranged at the opposite sides thereof adjacent the inner and outer ends of the same, respectively, with the inner end of said bed

14 pivoted, as at 20, so that said ramp section 13 may swing vertically on the pair of piles 18 at its inner end. Preferably, the pivots 20 take the form of headed trunnions extended through suitable cap members 21 on said piles 18. At the outer end thereof, said bed 14 is provided with laterally extending, double-headed guide trunnions 22 fixed at one end in suitable plates 23 secured in any desired manner to the side walls 16 and having the other ends thereof playing in vertical, arcuate slots 24 in hollow guides 25 suitably fixed on the upper ends of the pair of piles 19, the slots 24 being arranged to permit the outer end of the ramp section 13 to swing upwardly and downwardly freely.

A pilot slip is provided at the outer end of the pilot ramp section 13 comprising a pair of side wings or members 26 of elongated form pivoted at inner ends thereof, as at 27, to the outer ends of the guide walls 16 for swinging about vertical axes thereon and connected together at their outer ends in outwardly diverging relation by a bottom cross bar 28 pivoted at the ends thereof, as at 29, to said wings 26. The wings 26 terminate at the other ends thereof in outwardly flaring extensions 30 serving as end buffers thereon in a manner which will be apparent. The side wings 25, including the extensions 30, are padded, as at 31, in the same manner as the guide walls 16. A pair of floats 32 are suitably fixed to the outer sides of the side wings 25 adjacent the extensions 30 and which may be of any type sufficiently buoyant to cause the described pilot slip and the floating ramp section 13 to rise and fall with the tide and to maintain the side wings 25 and guide walls 16 above water level at all times from the inner end of said ramp section 13 outwardly, and with a transporting car on said floating section 13 submerged at the outer end of said section. It will be understood that the inner end of the floating ramp section 13 is pivoted so that the bed 14 and the tracks 15 at their inner ends are permanently, substantially level with the outer ends of the bed 3 and the tracks 5, respectively.

As will now be seen, the described side wings 26 are laterally swingable in unison to form a tapering slip for directing a flying boat, such as represented at 33, to the floating pilot section 13 regardless of the water level and from various angles.

For swinging the described pilot slip section laterally, a cable 34 is preferably connected at its ends to the floats 32, as represented at 35, extended along opposite sides of the floating section 13 and the landing ramp 2 to suitable guide pulleys 36 on the platform 1 with a stretch of said cable, intermediate said pulleys, suitably attached to a power reel 37 for winding up said cable to exert pull on said ends alternately.

In conjunction with the foregoing, a transporting car, or truck, 38 is provided for transporting the flying boat 33, and which preferably comprises a flat bed 39 supported by wheel trucks 40 at each end of said bed, the bed being surrounded by end, skeleton cradle sections 41 constructed and arranged, in any suitable manner, to seat therein the hull, or fuselage, of a flying boat 33 without interfering with the wings of said boat or other parts appurtenant thereto. The described car 38 is designed to be propelled over the described tracks and to be run, in landing the flying boat 33, down onto the floating ramp section 13, and this operation may be man-

ually performed, or suitable power means may be utilized for propelling the car 38 if desired.

Means are provided whereby an incoming, or landing, flying boat 33 is adapted to pick up the car 38 when the latter is located on the floating ramp section 13, and whereby, under its own power, said boat will propel said car up said floating ramp section 13, and the landing ramp 2, and along selected tracks 8, 9, 10, as the case may be. The pick-up means comprises a hook member 42 provided on the tail end of the hull of the flying boat 33 to depend therefrom with a hooked end 43 turned forwardly, and a fan tail-like pusher frame 44 of rod-like metal extending from what constitutes the rear end of the bed 39 and which includes a rear, concave, central seat 45 for receiving said hooked end 43 of said member 42 therein.

Referring now to the use and operation of the described embodiment of my invention, the transporting car 38 is first run down onto the floating ramp section 13. In this connection, it should be explained that the weight of the car 38 swings the floating ramp section 13 downwardly in the water so that the cradle section 41 at the rear end of said car is submerged sufficiently to permit a flying boat 33 traveling on the water to pass over the rear end of the cradle section 41. The pilot slip wings 25 may then be swung to substantially align the slip with the line of forward travel of an approaching flying boat traveling on the surface of the water and said boat 33 is run into the slip. At this point, said wings 26 may be swung to align the flying boat 33 with the floating ramp section 13 and the car 38 thereon. As the flying boat 33 continues its progress over the water through the pilot slip, it is guided by the wings 25 into the floating pilot ramp section 13, and by the guide walls 16 of said section over the car 38 to center the hull, or fuselage, over said car. As said flying boat 33 reaches a proper position to seat in the cradle sections 41, the hooked member 42 picks up the pusher frame 44 with the end 43 caught in the seat 45. From this point, said boat 33, under its own power, propels the car 38 up the floating ramp section 13 onto the landing ramp 2 and during such progress of said car seats in the cradle sections 41 and propels said car 38 up the landing ramp 2 and onto whichever tracks 8, 9, 10 the car is directed by an operative. As will be understood, when the car 38 is manually propelled, it is manually held on the floating ramp section 13. In launching the flying boat 33, the car 38, with said boat thereon is merely run down the launching ramp 6 into the water sufficiently to displace said boat from the cradle sections 41 by floating the boat out of said sections in a manner which will be understood.

In the modified embodiment of my invention shown in Figures 12 to 13, a floating turntable 46 is provided at the outer end of the floating ramp section 47 and said ramp section is suitably mounted at its outer end for vertical swinging movement by pivot pins, as at 48, and for vertical floating movement by guides 49 into which said pins 48 extend and which are adapted to play vertically in cap members 50 on a pair of piles 51. The turntable 46 is mounted by pins 52 in suitable guide slots 53 in caps 54 on piles 55 so that said turntable may float upwardly and downwardly, and the turntable is provided with suitable floats 56. The outer end of the floating ramp section 47 is provided with floats, as at 56. The piles 55 rise from a cap-like annular support 57 rotatably mounted by means of roll-

ers 58 in a circular trackway 59 provided in a base member 60 of circular form suitably secured, as at 61, to a foundation 62 embedded in the bottom of the body of water, not shown. Side guide walls 65 are provided on the turntable 46 with flaring entrance ends 66. A pair of suitable gates 67 are hinged, as at 68 to the side walls 65 at the exit ends of the same and are provided with a suitable bolt form of latch 69' for maintaining the same closed. The support 57 may be used as a belt pulley for rotation by a suitably power-operated belt 70.

As will be understood, the described turntable 46 is designed to be used in lieu of the previously described pilot slip and to be rotated into different positions, shown in dotted lines in Figure 12, so that a flying boat may be entered into the space, or revolving slip, formed by the side walls 65 until blocked by the gates 67. After a flying boat has been run into said space or slip, the turntable 46 may be rotated to align the side walls 65 with side walls 69 on the floating ramp section 47 and the gates opened to permit the boat to pass through the same. Otherwise, the modified embodiment of the invention described is used in the same manner as the preferred embodiment.

The foregoing will, it is believed, suffice to impart a clear understanding of my invention without further explanation.

Manifestly, the invention as described is susceptible of modification without departing from the inventive concept, and right is herein reserved to such modifications as fall within the scope of the appended claims.

What I claim is:

1. Apparatus for landing flying boats approaching the same on a body of water comprising a stationary field, a landing ramp inclining from said field into the water with an outer end portion submerged, means to guide a flying boat to the outer end portion of said ramp comprising a floating pilot slip swingable laterally into different angular positions relative to the ramp, and a floating guide structure intermediate said ramp and slip confined against lateral movement.

2. Apparatus for landing flying boats approaching the same on a body of water comprising a stationary field, a landing ramp inclining from said field into the water with an outer end portion submerged, means to guide a flying boat to the outer end portion of said ramp comprising a floating pilot slip swingable laterally into different angular positions relative to the ramp,

and a floating guide structure intermediate said ramp and slip confined against lateral movement and pivoted for vertical swinging movement at the outer end of said ramp.

5. 3. Apparatus for landing flying boats approaching the same on a body of water comprising a stationary field, a landing ramp inclining from said field into the water with an outer end portion submerged, means to guide a flying boat to the outer end portion of said ramp comprising a floating pilot slip swingable laterally into different angular positions relative to the ramp, a floating guide structure intermediate said ramp and slip confined against lateral movement and pivoted for vertical swinging movement at the outer end of said ramp, a wheel-supported car for transporting the flying boat from said structure up the ramp and over said field, a track system for said car, and means to cause a flying boat passing through said structure to couple to said car whereby said boat may be operated to propel said car.

20 4. Apparatus for landing flying boats approaching the same on a body of water comprising a stationary field, a landing ramp inclining from said field into the water with an outer end portion submerged, means to guide a flying boat to the outer end portion of said ramp comprising a floating pilot slip swingable laterally into different angular positions relative to the ramp, a track system for said car, and means to cause a flying boat passing through said structure to couple to said car whereby said boat may be operated to propel said car.

25 5. Apparatus for landing flying boats approaching the same on a body of water comprising a stationary field, a landing ramp inclining from said field into the water with an outer end portion submerged, means to guide a flying boat to the outer end portion of said ramp comprising a floating pilot slip swingable laterally into different angular positions relative to the ramp, a floating guide structure intermediate said ramp and slip confined against lateral movement and to which said slip is swingably connected.

30 35 6. Apparatus for landing flying boats approaching the same on a body of water comprising a stationary field, a landing ramp inclining from said field into the water with an outer end portion submerged, means to guide a flying boat to the outer end portion of said ramp comprising a floating pilot slip swingable laterally into different angular positions relative to the ramp, a floating guide structure intermediate said ramp and slip confined against lateral movement and pivoted for vertical swinging movement at the outer end of said ramp, a wheel-supported car for transporting the flying boat from said structure up the ramp and over said field, a track system for said car, and means to cause a flying boat passing through said structure to couple to said car whereby said boat may be operated to propel said car, said car being provided with a cradle structure for seating a flying boat thereon.

40 45 50 55

FRANK J. WALTERS.
